LAMP LENS FOR AUTOMOBILES OR THE LIKE

Eugene Bordnat, Jr., Bloomfield Hills, Mich., assignor to
Ford Motor Company, Dearborn, Mich., a corporation
of Michigan

Filed Aug. 25, 1961, Ser. No. 66,506

Term of patent 7 years

(Cl. D48—32)

— FIG. — 4

— FIG. — 3

— FIG. — 5

FIG. 1 is a front elevational view of a lamp lens for automobiles or the like, showing my new design;

FIG. 2 is a rear elevational view thereof;

FIG. 3 is a side elevational view thereof;

FIG. 4 is a sectional view taken on the plane indicated by line 4—4 of FIG. 1; and

FIG. 5 is an enlarged fragmentary view of a portion of FIG. 4.

I claim:

The ornamental design for a lamp lens for automobiles or the like, substantially as shown.
